Patented June 8, 1915.

Henry B. Weiper
Inventor:

UNITED STATES PATENT OFFICE.

HENRY B. WEIPER, OF LOWER LAKE, CALIFORNIA.

DESIGN FOR A GRAVE-PROTECTING MONUMENT.

47,444.

Specification for Design.

Patented June 8, 1915.

Application filed March 29, 1915. Serial No. 17,949. Term of patent 7 years.

To all whom it may concern:

Be it known that I, HENRY B. WEIPER, a citizen of the United States, residing at Lower Lake, in the county of Lake and State of California, have invented a new, original, and ornamental Design for Grave-Protecting Monuments, of which the following is a specification, reference being had to the accompanying drawing, forming a part thereof.

The figure is a perspective view of a grave protecting monument, showing my new design.

I claim:

The ornamental design for a grave protecting monument, as shown.

HENRY B. WEIPER.

Witnesses:

J. A. KESEY,
JOHN H. PUQUE.
